UNITED STATES PATENT OFFICE.

WILLIAM MARTIN, OF WILKINSBURG, PENNSYLVANIA.

STREET-CAR FENDER.

No. 809,829.

Specification of Letters Patent.

Patented Jan. 9, 1906.

Application filed September 1, 1905. Serial No. 276,723.

To all whom it may concern:

Be it known that I, WILLIAM MARTIN, a citizen of the United States of America, residing at Wilkinsburg, in the county of Allegheny and State of Pennsylvania, have invented certain new and useful Improvements in Street-Car Fenders, of which the following is a specification, reference being had therein to the accompanying drawings.

10 This invention relates to certain new and useful improvements in street-car fenders.

The general type of construction involved is a fender which is manually or foot operated and which drops into working position 15 by gravity and which is returned by manual or foot operated means to the initial position and is held in such position by said means.

The fender more particularly embodies two sections—a stationary section supported 20 from beneath the body of the car and a section hinged to said stationary section and connected with the operating-lever by simple means. The operating-lever is given free movement by a spring-controlled dog which 25 is adapted to be released by the foot, means being provided for moving the lever so as to operate the connections and cause the hinged fender to assume a position with its end flush with the tracks or road-bed.

30 The detail construction will appear in the course of the description, in which reference is had to the accompanying drawings, in which like numerals of reference designate corresponding parts throughout the several 35 views, wherein—

Figure 1 is a side elevation showing a part of the car. Fig 2 is a top plan view thereof. Fig. 3 is an enlarged longitudinal section through the operating-lever. Fig. 4 is an 40 enlarged perspective view of the corner of the stationary fender, showing the manner in which it is hinged to the car.

The bottom 1 of the car is formed at the platform end thereof with an opening 2, and 45 secured to said platform adjacent to said opening are bearings 3 of a conventional form, in which is fulcrumed or centered at 4 a lever 5, provided with a foot-plate 6. A pawl 7 is also fulcrumed in said bearings in 50 the rear of said lever and is held to and in engagement with a notch 8 in said lever by means of a spring 9, having its one end secured to the floor of the car, as at 10, and bearing with its outer end against the rear

portion of the pawl 7. Fulcrumed to the 55 lower end of the lever 5 is a link 11, which has movement in bearings 12, supported beneath the car, and which has pivotal connection at its other end, as at 13, with a transverse rod 13^a, loosely mounted in oppositely-disposed levers 14, depending from the rod 13^a. Mounted beneath the floor in bracket-supports 15 is a stationary fender 16, which, as shown, is constructed of metal, although the ordinary rope mesh or any other fender 60 construction may be employed. The fender 16 carries in the rear thereof a pair of oppositely-disposed apertured brackets 17, in which is fulcrumed, as at 18, the levers 14, previously mentioned. The fender 16 constitutes what we will term for the sake of brevity the "stationary" fender, and hinged 70 to the end thereof is a fender 19. The fender 19 is hinged to the fender 16 by means of connecting-rod 20, which passes through the 75 bent portions 21 upon said fenders 16 and 19. The portions 21 are bent into substantially annular shape and severally interfit. Fulcrumed to the lower end of the levers 14, as at 22, are longitudinal rods 23, which extend 80 beneath the stationary fender 16 and the hinged fender 19 and are fulcrumed, as at 24, to depending brackets 25, carried by the latter. In order to strengthen the structure in its position depending from the car, curved 85 braces 26 are employed, which are connected to the fender 16, adjacent the bottom thereof, and to the bottom 1 of the car.

My invention is so constructed that the gravity of the hinged fender 19 would ordinarily be sufficient to depress the same when the lever 5 is released from engagement with the pawl 7; but should the bearings become choked and not work freely, so that the gravity action of the fender 19 is not sufficient to lower the same, a spring 27 is interposed in the slot 2 between the wall thereof and the lever 5, which at its lower end positively engages said lever and throws the latter forward, thereby insuring a positive operation of the various parts.

In operation should an obstacle rest upon the tracks 28 and it is desired to lower the hinged fender in position to engage said obstacle the motorman depresses the pawl 7 out 105 of the notch 8, and the spring 27 will then act to engage the lower end of the lever 5 and throw said lever forward. The link 11 is then

thrown forward, and the lower ends of the levers 14 are swung upon their fulcrums 18 to the rear and carrying with them the rods 23, which at their fulcrums 24 will swing the fender 19 downwardly and cause the same to assume the position shown in dotted lines in Fig. 1. The fender 19 will then lie flush with the surface of the tracks or the road-bed, so as to receive an obstacle lying upon said road-bed. When it is desired to restore the fender to initial or inoperative position, the motorman pushes forwardly the lever 5, and as the upper end of the same moves forwardly it will throw the link 11 to the rear, moving forward the lower ends of the levers 14 and in so doing, through the medium of the connecting-rods 23, raise the hinged fender 19. At the completion of this operation the spring 9 will act upon the pawl 7 to force the same into the notch 8, formed in the lever 5, and thereby lock said lever and the parts connected thereto against further operation.

It is obvious that various minor changes may be made in my invention both in the form 25 of the elements employed and in their positions upon the car. Such changes, however, will fall under the scope of the invention as defined by the appended claims. For example, see Fig. 4, in which the bent ends 21 of the stationary fender 16 are caused to overlap the body portion of the fender instead of merely meeting the same, as in Fig. 1. This construction, where the metal is of considerable weight, adds rigidity to the structure, 30 another example of change which must be made to answer certain variations in the street-car construction being the location of the fulcrum between the stationary fender 16 and the hinged fender 19. This fulcrum instead of being at an intermediate point between the fenders may be at any desired point, even entirely in the rear of the fender 16 or as far back as the supporting-bracket 15, as in dotted lines in Fig. 1.

Having fully described my invention, what 45 I claim is—

1. A fender embodying a stationary section supported beneath the floor of the car, and a section hinged thereto, a lever fulcrumed in bearings secured to the floor of the car, means 50 operatively connecting said lever with said hinged section, whereby to impart movement to the latter when said lever is moved, means to hold said lever normally against movement, means for positively imparting 55 movement to said lever when released by said holding means.

2. A fender embodying a stationary section, a section hinged thereto, a lever fulcrumed in bearings secured to the floor of the 60 car, means operatively connected to said hinged section and to said lever, spring-held means for holding said lever, and adapted to be released from engagement therewith, means for imparting movement to said lever 65 when released by said holding means.

3. A fender embodying a stationary section, supported by the floor of a car, and a section hinged to said stationary section, a lever fulcrumed in bearings secured to the 70 car, means operatively connecting said lever with said hinged section whereby to vary the movement of the same with the movement of said lever, means to lock said lever against movement, means for imparting movement 75 to said lever when released by said locking means, said lever being adapted to be moved by the foot, and thereby restored to initial position, and means for returning said locking means into positive engagement with said 80 lever when the latter has been restored to initial position.

In testimony whereof I affix my signature in the presence of two witnesses.

WILLIAM MARTIN.
